UNITED STATES PATENT OFFICE.

FRANK J. VIERLING AND ANDREW KVORNING, OF MINNEAPOLIS, MINNESOTA,
ASSIGNORS TO BROWN & BIGELOW, OF ST. PAUL, MINNESOTA, A CORPORATION
OF MINNESOTA.

PENCIL.

1,373,278.

Specification of Letters Patent. Patented Mar. 29, 1921.

Application filed April 25, 1918. Serial No. 230,800.

To all whom it may concern:

Be it known that we, FRANK J. VIERLING, a citizen of the United States, and ANDREW KVORNING, a subject of the King of Denmark, residing at Minneapolis, in the county 5 of Hennepin and State of Minnesota, have invented certain new and useful Improvements in Pencils; and we do hereby declare the following to be a full, clear, and exact 10 description of the invention, such as will enable others skilled in the art to which it appertains to make and use the same.

Our invention has for its object to provide an improved pencil; and to this end, 15 it consists of the novel devices and combinations of devices hereinafter described and defined in the claims.

In the accompanying drawings, which illustrate the invention, like characters indicate like parts throughout the several 20 views.

Referring to the drawings:

Figure 1 is an elevation of the improved pencil;

Fig. 2 is an enlarged view of the improved pencil, principally in longitudinal central section;

Fig. 3 is a detail view of the friction device, in section, taken on the line 3-3 of 30 Fig. 2;

Fig. 4 is a detail view of the ball clutch, in section, taken on the line 4-4 of Fig. 2;

Fig. 5 is a detail view, in section, taken on the line 5-5 of Fig. 2;

Fig. 6 is a view corresponding to Fig. 2, with the exception that the lead feeding mechanism is moved into a position to release the clutch;

Fig. 7 is an elevation of the lead holding 40 channel;

Fig. 8 is an elevation of the pencil cap;

Fig. 9 is a fragmentary elevation of the point end of the pencil, in section, illustrating a slight modification; and

Fig. 10 is a fragmentary longitudinal section, taken on the line 10-10 of Fig. 9.

The numeral 11 indicates a tubular outer casing having a contracted lower end or point 12. Secured within the point 12 is an 50 axially located lead holding channel or tube 13, having a funnel-like upper end. As shown, the tube 13 is frictionally secured, at its lower end, to the point 12, by longitudinally splitting said tube, so that in forcing 55 the same into position said lower end there-

of is slightly contracted. The rim of the upper end of the tube 13 closely engages the internal walls of the casing 11 and thereby holds the upper end of said tube against axial movement.

Rigidly but removably secured within the outer casing 11 is an inner casing 14, the lower end of which tightly fits within the funnel-like upper end of the tube 13. 60 Mounted in the upper ends of the inner casing 11, with freedom for axial sliding movement, is a plunger head 15, the upper end portion of which is reduced in diameter to afford a shoulder 16. This shoulder 16 engages an inturned flange 17 on the upper 65 end of the inner casing 14 and prevents the plunger head 15 from being withdrawn therefrom. The upper end of the plunger head 15 is made hollow to afford a chamber or receptacle 18 for extra leads Z. The lead 70 in the point of the pencil is likewise identified by the letter Z. A cap or finger piece 19 is telescoped onto the reduced upper end of the plunger head 15 and is frictionally held thereon by longitudinally splitting said 75 plunger head so that the same is slightly contracted under the telescoping movement of said cap thereon.

Secured to the lower end of the plunger head 15 is a long tubular push plunger 20, 80 axially located with respect to the tube 13, and affords a guide for an ejector 21 in the form of a long rod, the lower end of which is adapted to enter the tube 13 and impart a step by step movement to the respective 85 lead Z. Near the lower end of the inner casing 14 is a transverse partition 22, having an axial bore through which the ejector 21 works. A coiled spring 23 encircling the ejector 21 is compressed between the lower 90 end of the push plunger 20 and partition 22 and normally holds the said push plunger, plunger head, and cap in their 95 uppermost positions.

Steps of movements are imparted to the 100 ejector 21 under successive downward movements of the cap 19 by one-way clutch. This clutch comprises ball members 24 and a cone member 25, which has a slight limited axial movement in respect to the push 105 plunger 20. Said ball members 24 of the clutch are mounted in radial seats 26, formed in the push plunger 20, which works through an axial opening in the cone member 25 of said clutch. A coiled spring 27 110

encircling the push plunger 20 is compressed between the upper end of the cone member 25 of the clutch and a collar 28 on said push plunger. The ball members 26 of the clutch 5 are released from the cone member 24 thereof by an annular shoulder 29, pressed from the inner casing 14, between said cone member and the partition 22.

The clutch is so arranged that the initial 10 downward pressure on the cap 19 will cause said clutch to impart a downward step of movement to the ejector 21, and hence to the engaged lead Z. During this initial movement of the cap 19 the spring 27 will cause 15 a common movement of the cone member 25 with the push plunger 20. A further movement of the cap 19 will carry the lower end of the cone member 25 of the clutch into engagement with the shoulder 29. A still 20 further downward movement of the push plunger 20 will carry the ball members 24 of the clutch out of engagement with the cone member 25 thereof, and thereby release the ejector 21. When the cap 19 is released 25 the spring 23 will lift the push plunger 20 and thereby carry the ball members of the clutch into the cone member 25 thereof and return the same to normal position. During 30 the return movement of the push plunger 20 the clutch, of course, will be inoperative and, therefore, the ball members 24 thereof will not grip or hold the ejector 21.

A friction device is provided for holding the ejector 21 during the return movement 35 of the clutch, push plunger and cap to normal position. This friction device, as illustrated in Figs. 2 and 3, comprises a pair of balls 30 and a transversely split clamping ring 31, which bears upon said balls and 40 yieldingly presses the same onto the ejector 21. The friction balls 30 are mounted in radial seats 32, formed in the reduced upper end of a plug 33, which closes the lower end of the inner casing 14. The upper end of 45 the plug 33 engages the partition 22, which holds the clamping collar 31 against axial movement from said plug. The ejector 21 freely works endwise through a bore in the plug 33.

50 From the above description it is evident that the one-way clutch 24-25 securely holds the ejector 21 so that the same acts as a base of resistance for the lead Z when writing with the pencil. After the lead is 55 worn down to the point 12, a downward pressure on the cap 19 will impart a step of movement to the ejector 21 which, in turn, will impart a step of movement to the engaged lead Z, and thereby slightly project the same outward of the point 12. A new lead may be placed in the tube or 60 holder 13 by inserting the same into the point 12 while holding the cap 19 pressed inward so as to release the clutch and there- 65 by permit an inward movement of the

ejector 21. If desired, the cap and inner casing, together with the parts carried thereby, may be removed from the outer casing and a new lead dropped in the upper end of said outer casing and which lead will 70 be directed into the tube 13 by the funnel-shaped upper end thereof.

The construction shown in Figs. 9 and 10 is the same as that shown in the other figures, with the exception that the friction 75 device comprises a pair of yieldingly pressed fingers 34, which engage opposite sides of the ejector 21 and yieldingly hold said ejector against upward movement under the return movement of the push plunger. As shown, the fingers 34 are formed from the single piece of spring metal having, in its transverse portion, an axial opening 80 for the ejector 21. Opposing shoulders 35, in the inner tube 14, hold the spring 85 fingers 34 against axial movement within said inner casing.

What we claim is:

1. A pencil comprising a casing and a lead feeding device including an ejector, 90 ball clutch means adapted to engage said ejector to move it in one direction, means for releasing said ball clutch and frictional means adapted to hold said ejector against free longitudinal movement.

2. A pencil, a casing, a lead feeding device comprising an ejector adapted to freely engage the butt end of the marking lead, 100 a ball clutch adapted to engage said ejector to impart a step by step movement by repeated longitudinal movements of said clutch and means for holding said ejector during the inoperative movement of said clutch to allow said clutch to move said ejector and engage at different points, said 105 clutch being adapted to normally hold said ejector against backward movement in said casing.

3. A pencil, a casing, a lead ejector rod adapted to constantly engage and form an 110 abutment for the lead in said pencil, a clutch adapted to normally engage said rod under spring tension, releasing means adapted to release said clutch from engagement with said rod when said clutch is moved in 115 extreme position in one direction and resilient means adapted to engage said rod to hold it against free longitudinal movement.

4. A pencil comprising a casing having, at its lower end, a channel for frictionally 120 holding a piece of lead, a push plunger mounted in the casing, a spring normally holding the push plunger in its uppermost position, a lead ejector mounted in the push plunger with freedom for endwise movement, a one-way clutch normally holding the ejector against a movement away from the lead and for imparting a variable step 125 of movement to said lead under a downward movement of the push plunger, and 130

a friction device for holding the ejector during the return movement of the push plunger.

5. A pencil comprising a casing having, in its lower end, a channel for frictionally holding a piece of lead, a push plunger mounted in the casing, a spring normally holding the push plunger in its uppermost position, a lead ejector mounted in the push plunger with freedom for endwise movement, a one-way clutch normally holding the ejector against a movement away from the lead and for imparting a variable step of movement thereto under the initial 10 downward movement of the push plunger, means for rendering the clutch inoperative at the limit of the downward movement of the push plunger, and a friction device for holding the ejector during the return movement of the push plunger.

6. A pencil comprising a casing having, at its lower end, a lead holding channel, a push plunger mounted in the casing, a spring normally holding the push plunger in its uppermost position, an ejector mounted in the push plunger with freedom for endwise movement, a one-way clutch including a ball member carried by the push plunger, and a cone member having a limited axial movement in respect to the push plunger, a spring operative on said cone member to normally hold the ball member

in an operative position against the ejector for imparting a step of movement to the lead under the initial downward movement 35 of the push plunger, a shoulder with which the cone member of the clutch engages during the downward movement of the push plunger to release said ejector, and a friction device for holding the ejector during 40 the return movement of the push plunger.

7. A pencil, including a casing, a lead feeding mechanism comprising a push plunger having a hollow rear end, a ball clutch mounted on the forward end of said plunger, an ejector rod adapted to form an abutment for the marking lead in said pencil, resilient means adapted to hold said clutch under spring tension in engagement with said rod, frictional means adapted to hold 50 said rod against free longitudinal movement and means for rendering said clutch inoperative at the limit of its movement in one direction to release said rod and allow the marking lead in said pencil to be moved 55 back into said casing while said clutch is held in its released position.

In testimony whereof we affix our signatures in presence of two witnesses.
